FORTUNE TELLING DOLL

Stevie S. Whitefeather, 748 S. Irolo Ave.,

Los Angeles, Calif. 90005

Filed Dec. 14, 1964, Ser. No. 83,008

Term of patent 14 years

(Cl. D34—4)

Fig. 1.

Fig. 3.

Fig. 2.

FIG. 1 is a perspective view taken from the left front of a fortune telling doll, showing my new design;

FIG. 2 is a side elevational view, taken from the right side of the doll shown in FIG. 1; and

FIG. 3 is a rear elevational view of the doll.

I claim:

The ornamental design for a fortune telling doll, as shown.
